ELMER E. IZER, OF POMONA, CALIFORNIA, ASSIGNOR TO THE POMONA MANUFACTURING COMPANY, OF POMONA, CALIFORNIA, A CORPORATION OF CALIFORNIA.

PUMP-ROD SHOE.

1,148,777.

Specification of Letters Patent. Patented Aug. 3, 1915.

Application filed September 9, 1914. Serial No. 860,935.

To all whom it may concern:

Be it known that I, ELMER E. IZER, a citizen of the United States, residing at Pomona, in the county of Los Angeles, 5 State of California, have invented a new and useful Pump-Rod Shoe, of which the following is a specification.

This invention relates to pumps and particularly to those in which the pumping means is located at, or near the bottom of a well, being actuated through pump rods by a suitable pumping head located at the surface of the ground. In the usual form of such pumps the pump rods are in tension 10 when performing work and tend to assume a straight line. In deep wells there are often bends in the pump column so that the pump rods tend to rub on the pump column, thereby abrading both the pump 15 rods and the pump column.

The principal object of my invention is to provide means for reducing this abrasion to a minimum.

Further objects and advantages will appear hereinafter.

Referring to the drawings which are for illustrative purposes only: Figure 1 is an elevation, partly in section, of my invention applied to a deep well. Fig. 2 is a 30 section on the plane x^2-x^2 of Fig. 1. Fig. 3 is a perspective view of the shoe employed in my invention.

In these drawings a well casing 10 is driven vertically in the ground and a pump 35 column 11 is placed therein, the pump barrel in which the piston works being in open communication with the interior of the pump column 11, the fluid to be pumped being raised vertically through this pump 40 column. Pump rods 12 and 13 pass upwardly through the pump column 11 and connect the piston with the pumping head which is placed on the top of the ground. The pump rods 12 and 13 are connected by 45 a threaded coupling 14.

The well casing 10 is often bent out of line due to various causes. The best practice in drilling water wells is to sink a square shaft to water level, removing all 50 boulders. The well casing is then supported in a vertical line in this shaft, loose material being filled in around it. The well 55 below water line is then drilled, and the casing is forced downwardly generally by means of hydraulic jacks.

In drilling through soft material large stones, such as that illustrated at 15, may be located on the line of the drill which will be considerably deflected thereby. As the well casing falls the line of the drill may 60 be considerably deflected as illustrated, the pump column 11 being similarly deflected.

The pump rods tend to assume a straight line, being flexible and under a considerable tension, and where the pump column has 65 been deflected the coupling 14 will tend to rub on the side of the pump column. This tends to wear holes in the pump column and also to wear off the coupling 14 as will readily be understood, particularly as the 70 coupling is of small diameter as compared to the pump column and the line of contact between the coupling and the column is a narrow line under considerable pressure.

For the purpose of distributing the pressure 75 of the pump rods 12 and 13 over a wide area on the interior of the pump column I provide a shoe 16 which has a central opening 17, large enough to fit loosely over the pump rods 12 and 13, and openings 18 at either 80

side thereof, these openings being added for the purpose of increasing the effective area through which the rising stream of 85 water may flow. The shoe 16 is illustrated as placed over the rod 12, a collar 19 being shrunk on the pump rod 12 above the shoe 16, the distance between the collar 19 and the coupling 14 being just sufficient to allow 90

the shoe to turn freely without sliding axially. The sides of the shoe 16 are made on the same radius as the interior of the pump column so that the shoe 16 bears evenly over a large bearing area, the shoe being made considerably longer than the 95 coupling.

The result of applying my invention to the pump rods of a well having a crooked pump column is that when the rods 12 and 13 are reciprocated vertically the shoe 16 provides a large bearing area against the interior of the column so that the wearing of the column and shoe becomes negligible and the well may be pumped for long periods without danger of perforating the 100 pump column.

I claim as my invention:

1. In a well, a pump column, a series of pump rods reciprocated vertically in said column, and a series of shoes having sides curved to fit the inside of the pump column, 110

said shoes being loosely secured to said pump rods.

2. In a well, a pump column, a series of pump rods reciprocated vertically in said column, and a series of shoes having sides curved to fit the inside of the pump column, said shoes being secured on said pump rods in such a manner that they move with said pump rods and adjust themselves about the 10 axis of said pump rods to suit the position of said column.

3. In a well, a pump column, a series of pump rods reciprocated vertically in said column, a series of couplings each connecting a pair of said pipe rods, a collar shrunk on each of said pipe rods, and a shoe having its sides curved to fit the inside of said pump column, said shoes being loosely mounted between each of said collars and its corresponding coupling. 15 20

4. In a well, a pump column, a series of pump rods reciprocated vertically in said column, a series of couplings each connecting a pair of said pipe rods, a collar shrunk on each of said pipe rods, and a shoe having its sides curved to fit the inside of said pump column, each of said shoes being mounted on said pump rods between a collar and its adjacent coupling in such a manner that the shoe is free to turn about the axis of said 25 30 pump rods but is restrained from moving along this axis.

In testimony whereof, I have hereunto set my hand at Pomona, California, this 27th day of Aug., 1914.

ELMER E. IZER.
